COIL SYSTEM.

Application filed May 22, 1926. Serial No. 111,074.

This invention relates to an inductance coil system and relates more particularly to a coil system especially designed for radio circuits of the sharply tuned or selective type; and has special reference to the provision of a coil system which is self-shielded magnetically and electrostatically.

As is well known, it is a desideratum in certain types of selective and sensitive 10 radio receiving apparatus and in apparatus employable near transmitting stations to construct the inductance coils of the receiving apparatus so that they are uncoupled magnetically and electrostatically to other 15 coils and apparatus in the receiving circuit or to the transmitting apparatus. To accomplish the magnetic uncoupling of the coils to other apparatus, various types of coil windings have hitherto been designed, 20 such as double D windings, toroid windings and binocular coils; and to accomplish the electrostatic uncoupling of such coils to surrounding apparatus, it has been common to employ separate electrostatic shields. 25 These prior types of coil windings have, however, been found insufficient to produce the desired results on account of their relatively large external fields near the coil which produce considerable coupling to 30 other parts and even between similar coils when placed at a moderate distance apart. To reduce the intermagnetic couplings between similar coils in a radio receiving set with the use of such prior structures, it 35 has been found necessary to so relatively arrange the coils one with respect to the other in the radio receiving set as to minimize the reacting fields. Other structural difficulties, such as the large volume of 40 winding required and the difficulty of winding methods, have also hindered the use of these prior and known types of winding coils.

A prime desideratum of my present invention resides in the provision of an inductance coil system designed and constructed so that the external magnetic field is reduced to such a minimum that the coil is substantially decoupled magnetically from 45 surrounding apparatus and may be placed in close proximity to other similar coils of a radio receiving system without intermagnetically reacting with the same.

A further prime desideratum of the 50 invention resides in the provision of a coil system which is self-electrostatically shielded, that is, which requires no additional or separate electrostatic shield structure, the coil system being so designed and constructed that even when employed in a sharply tuned circuit, the same will be so perfectly shielded electrostatically that the hand of the operator may be brought to touch and surround the coil structure without detuning the circuit.

It is a further principal object of my present invention to so design and construct the inductance coil system that the mathematical and empirical conditions which satisfy the relations to produce the magnetic shielding also satisfy the relations to produce the static shielding so that the coil system is both electromagnetically and electrostatically decoupled from surrounding apparatus, permitting not only the close arrangement of a plurality of coil structures to produce a compactly organized radio receiving set, but permitting the same to be constructed without the use of electrostatic shielding devices.

To the accomplishment of the foregoing and such other objects as will hereinafter appear, my invention consists in the elements and their relation one to the other as hereinafter more particularly described and sought to be defined in the claims; reference being had to the accompanying drawings which show the preferred embodiment of my invention, and in which:

Fig. 1 is a cross-sectional view of the coil system of my invention, and

Fig. 2 is a view of the same showing the relation between the magnetic field of the unshielded inner coil and the residual magnetic field of the coil system as a whole.

Referring now in detail to the drawings; and having reference first to Fig. 1 thereof, the coil system of my invention is shown to comprise an inner coil section A and an outer coil section B both preferably made in the form of solenoids arranged in coaxial relation, the inner coil section being wound on a drum 10 made of insulating material and the outer coil section being wound on a drum 11 made of insulating material, the said coil sections being related in the manner specified hereinafter so that the outer coil section B forms a magnetic and electrostatic shield for the inner coil section A.

The coil sections A and B are connected together at contiguous ends by the conductor 12 so that the instantaneous currents

traversing the coil sections are in opposite directions, or in other words, so that opposing fluxes of different magnitudes are produced in the core of the inner coil section

5 A. Preferably as shown the outer coil joins the inner coil at the same axial end so that the two coils may be wound in the same direction. The free end 13 of the inner coil section A is the high potential end and is 10 connected to the high potential point of the radio receiving circuit, and the free end 14 of the outer coil section is the ground end and is connected in use to a point of ground potential in the radio receiving circuit. For 15 reasons to be pointed out hereinafter, the outer coil preferably overlaps the inner coil and preferably so that the line joining their ends makes an angle of approximately 45° with the axis of the coils, as clearly shown 20 in Fig. 1 of the drawings.

To produce the magnetic decoupling of the coil system, I have discovered that the ratio of the turns of the two coil sections must bear a definite and quite accurate relation 25 to the ratio of the areas of the two coils. This relation is that the product of the area and the number of turns on one coil section must be substantially equal to the product of the area and the number of turns of the 30 other coil section. The satisfaction of this condition reduces to a minimum the magnetic coupling between the coil system and a uniform magnetic field, as well as the magnetic coupling of the coil system with other 35 similar coils. This will be best understood when it is seen that if the coil system of my invention be placed in a uniform magnetic field of variable intensity, which field is directed for point of illustration along the 40 axes of the coils, the E. M. F. induced in the inner coil section is equal to the E. M. F. induced in the outer coil section, since the induced E. M. F. in a coil section is a linear function of the number of turns and the 45 total flux threading the coil. Since the product of the area and number of turns for one coil is equal to the product of the number of turns and the area for the other coil, it follows that the induced E. M. F.'s 50 are equal. Conversely, it will therefore be seen that the resultant field at a distance is zero, since the field produced by one coil section neutralizes at a distance the field produced by the other coil section. If the 55 field be not parallel to the axis as assumed, the same condition exists, since the field threading the coil is to be taken as the product of the field intensity and the cosine of the angle between the coil axis and the direction of the field, this angle being the 60 same for both coil sections.

To produce the static decoupling or shielding of the coil system, I have discovered that the coil system should be so constructed that the self-inductance of the outer coil section

B be made substantially equal to the mutual inductance between the two coil sections A and B. When this condition is satisfied, there results the novel effect of no potential drop along the outer coil due to the high frequency currents flowing; so that the whole surface of the outer coil is at substantially one potential. If this potential be made the ground potential as shown in the preferred use of the coil system, it will be 75 seen that the coil system is substantially completely electrostatically shielded.

To make the self-inductance of the outer coil section B equal to the mutual inductance between the coils, I have found first that 80 the ratio of the turns of the two coils must bear the same relation to the ratio of the area of the two coils as is necessary to satisfy the requirement of producing the magnetic shielding of the coil system hereinbefore 85 described. Thus the product of the area and number of turns of one coil should be equal to the product of the area and the number of turns of the other coil. After 90 satisfying this condition, which is the same for producing magnetic decoupling, it is generally necessary only to make the length of the outer coil slightly greater than the length of the inner coil, as clearly shown 95 in the drawings. This difference in coil 100 length may be utilized as shown to improve the electrostatic shielding of the high potential end of the inner coil, or, where this is not of primary importance, the inner and outer coils may be related symmetrically 105 with a little overhanging of the outer coil at each end. The latter slightly impairs the electrostatic shielding of the high potential end of the inner coil but slightly improves the magnetic shielding of the coil system. 110

When exact compliance with the last-mentioned condition is effected, I have found that it is possible to place one's hands about the outer coil without detuning, even though this coil be connected in a sharply 115 tuned circuit.

To produce a coil system of high efficiency, I have found that the ratio of areas of the coil sections should bear a given relation. Generally the ratio of areas of the outer to the inner coil section may be between 5 to 1 and 1½ to 1, and for producing the greatest efficiency the ratio of areas should be about 2, 2.1 and 2.2 for coils having ratios of 1.26, 1.58 and 2.1 respectively, of outer coil diameter to length. These area ratios are considered desirable because they give a maximum inductance for a given length of coil system having a constant outside diameter 120 when the inner coil is wound with a constant number of turns. This is a practical commercial limitation because other electrical and structural conditions impose certain limitations on coil diameters and coil lengths. The maximum number of turns per inch that 125 130

can be wound on the solenoid form is usually determined by the wire diameter especially at short waves where multilayer or banked windings cause a large decrease in coil efficiency.

5 Where the area ratio of outer coil to inner coil is about 2, I also obtain a high degree of static shielding with low distributed capacity in addition to obtaining maximum inductance with minimum resistance.

10 The results of magnetic and electrostatic shielding produced by my coil construction may also be visualized by consideration of the magnetic and electrostatic fields produced by the inter-acting coil sections. Magnetically considered, the magnetic flux through the inner coil due to the current in the inner coil, which flux is the more intense flux, is slightly reduced by the opposing flux through the inner coil due to the current in the outer coil. The inductance of the coil system arises primarily because the inner coil section has in its core a relatively intense magnetic field which is only partially neutralized by the flux of the outer coil. This partially neutralized flux within the coil has for its return path the annular space between the coils. That portion of the flux of the inner coil which would tend to return outside the outer coil is neutralized by the return flux of the outer coil. It follows, therefore, that the outer coil section confines the magnetic flux and is effective as a magnetic shield.

15 Electrostatically considered, we may first assume that we may neglect the potential drop along the outer coil section due to the resistance of the coil, since for the sharply tuned circuits in which these coils are to be used, the ratio of inductive to resistive drop is greater than 100 to 1. Now the inductive drop along the outer coil must be due to the magnetic flux linkages with this coil. Since practically the entire flux threading the coil system passes through the core of the inner coil and back in the annular space between the coils, there is no resultant flux linkage with the outer coil. This statement is to be modified only with respect to the residual flux which I have found issues radially from the center of the coil system and tends to produce neutralizing flux linkages in the halves of the outer coil as illustrated in Fig. 2 of the drawings, which will be referred to hereinafter. Looking at the phenomenon from the viewpoint of self and mutual inductances, the inductive drop along the outer coil due to its self-inductance is neutralized by the voltage drop due to the induced voltage arising from the mutual inductance of the two coils, these being equalized. Similarly the voltage drop along the inner coil is neutralized in part by the mutual inductance between the coils, but the self-inductance of the inner coil being

much greater than the self-inductance of the outer coil, the fraction of inductance of the inner coil lost due to the reverse mutual is inconsequential.

20 The manner of designing and constructing the coil system of my present invention will in the main be fully apparent from the above detailed description thereof. The uses and the manifold advantages, especially in radio frequency circuits of the tuned and selective types, will, it is thought, be also manifest from the above. To show the substantial elimination of the magnetic field surrounding the coil system, I reproduce in Fig. 2 an empirical graph showing (the bottom half of the graph) the comparatively large magnitude of the magnetic field due to the unshielded inner coil and showing by comparison (in the upper half of the graph) the small magnetic residual field of the coil system as a whole. Thus it will be seen, viewing Fig. 2 of the drawings, that while the inner coil (unshielded) has a value of 175 at a point along the axis of the coil, the value of the residual when the coil is connected to its outer shielding section falls at the same point to a value too small for measurement. Comparing points along a central line normal to the axis of the coil, the field of the unshielded coil at a point from the coil center equal to four times the radius of the coil is 104, while a similar point of the shielded coil has a recorded value of 6.

25 While I have shown and described my invention in the preferred form, it will be apparent that many changes and modifications may be made in the structure disclosed without departing from the spirit of the invention, defined in the following claims.

30 I claim:

1. A coil system comprising an inner coil section and an outer coil section connected to produce opposing fluxes of different magnitudes in the core of the inner coil section, the product of the number of turns and area of the inner coil section being related to the product of the number of turns and area of the outer coil section to produce neutralizing magnetic fields at a distance.

opposite directions, the product of the number of turns and area of the inner inductance coil section being equal to the product of the number of turns and area of the outer shielding coil section.

4. A coil system comprising inner and outer coaxially arranged cylindrical coil sections connected so that the instantaneous currents traversing the same are in opposite directions producing opposing fluxes of different magnitudes in the core of the inner coil section and a flux in the annular space between the coil sections, the product of the number of turns and the area of the inner coil section being equal to the product of the number of turns and area of the outer coil section.

5. A coil system comprising an inner coil section and an outer coil section connected so that the instantaneous currents traversing the same are in opposite directions, the ratio of areas of the outer to the inner coil sections being between five to one and one and one-half to one, and the product of the number of turns and the area of the inner coil section being equal to the product of the number of turns and area of the outer coil section.

6. A coil system comprising an inner coil section and an outer coil section connected so that the instantaneous currents traversing the same are in opposite directions, the ratio of areas of the outer to the inner coil sections being substantially two to one, and the product of the number of turns and the area of the inner coil section being equal to the product of the number of turns and area of the outer coil section.

7. A coil system comprising an inner coil section and an outer coil section connected to produce opposing fluxes of different magnitudes in the core of the inner coil section, the self-inductance of the outer coil section being equal to the mutual inductance between the coil sections, whereby the outer coil section forms a static shield for the coil system.

8. A coil system comprising inner and outer coaxially arranged cylindrical coil sections connected to produce opposing fluxes of different magnitudes in the core of the inner coil and a flux in the annular space between the coils, the self-inductance of the outer coil section being equal to the mutual inductance between the coil sections whereby the outer coil section forms a static shield for the coil system.

9. A coil system comprising inner and outer coaxially arranged cylindrical coil sections connected to produce opposing fluxes of different magnitudes in the core of the inner coil and a flux in the annular space

between the coils, the self-inductance of the outer coil section being equal to the mutual inductance between the coil sections and the outer coil section being made of a length slightly greater than the inner coil section whereby the outer coil section forms a static shield for the coil system.

10. A coil system comprising an inner coil section and an outer coil section connected to produce opposing fluxes of different magnitudes in the core of the inner coil section, the product of the number of turns and area of the inner coil section being related to the product of the number of turns and area of the outer coil section to produce neutralizing magnetic fields at a distance and so that the self-inductance of the outer coil section is equal to the mutual inductance between the coil sections.

11. A coil system comprising an inductance coil section and a shielding coil section connected thereto, the area turns of the coil sections being related to produce neutralizing magnetic fields at a distance and so that the self-inductance of the shielding coil section equals the mutual inductance between the coil sections, whereby the shielding coil section forms a static and magnetic shield for the inductance coil section.

12. A coil system comprising an inner inductance coil section and an outer shielding coil section connected so that the instantaneous currents traversing the same are in opposite directions, the product of the number of turns and area of the inner inductance coil section being equal to the product of the number of turns and area of the outer shielding coil section, and the length of the outer coil section being slightly greater than the length of the inner coil section whereby the outer coil section forms the static and magnetic shield for the coil system.

13. A coil system comprising an inner coil section and an outer coil section connected so that the instantaneous currents traversing the same are in opposite directions, the ratio of areas of the outer to the inner coil sections being substantially two to one, and the product of the number of turns and the area of the inner coil section being equal to the product of the number of turns and area of the outer coil section, and the length of the outer coil section being slightly greater than the length of the inner coil section whereby the outer coil section forms the static and magnetic shield for the coil system.

Signed at New York city, in the county of New York and State of New York, this 18th day of May, A. D. 1926.

LESTER L. JONES.
